UNITED STATES PATENT OFFICE.

HOWARD R. SARGENT, OF SCHENECTADY, NEW YORK, ASSIGNOR TO
GENERAL ELECTRIC COMPANY, A CORPORATION OF NEW YORK.

FUSE-BOX.

SPECIFICATION forming part of Letters Patent No. 696,497, dated April 1, 1902.

Application filed August 29, 1900. Serial No. 28,431. (No model.)

To all whom it may concern:

Be it known that I, HOWARD R. SARGENT, a citizen of the United States, residing at Schenectady, county of Schenectady, State of New York, have invented certain new and useful Improvements in Fuse - Boxes, (Case No. 1,482,) of which the following is a specification.

This invention relates to fuse-boxes; and 10 its specific embodiment disclosed herein is in a contact device through which connection is made from main to auxiliary circuits.

Of the drawings, Figure 1 is a plan view showing the interior of the base of the contact 15 device. Fig. 2 is a plan of the under side of the cover. Fig. 3 is a section along the line X X of the base and cover as assembled, and Fig. 4 is a section of the assembly, taken through the contacts E and U.

20 Hitherto in fuse-boxes it has been customary to provide a chamber for the fuse, the latter being connected at its ends to two terminals. In such cases unless the fuse is of impractically great length there is danger after 25 the fuse blows of an arc being maintained for a greater or less length of time across the terminals, and thus seriously or totally damaging the entire device. My invention consists of a means for preventing danger of this 30 sort.

Fig. 1 represents the base B, of suitable insulating material, such as porcelain, to which terminals L are secured for the reception of the line-wires. The base is formed with countersunk screw-holes S, whereby it is adapted 35 to be suitably secured to a ceiling or wall. A rim K is formed on the upper part of the base to form a large cavity, which is divided into four parts by the ridges R' and Q'. After the 40 cover is placed on the base these four divisions of the cavity are made separate chambers. Spring-contacts U are secured to the terminals L and are adapted to be engaged by terminals in the cover to complete the circuit. 45 and secure the base and cover together, as described hereinafter. After the assembly the cover C fits closely the top of the rim K, and the holes V in the rim K serve as vents for the chambers.

50 Fig. 2 shows the under side of the cover C, which is made of similar material to that of

the base B. It is formed with a depending rim J, divided into two parts, which rim fits within the rim K of the base B to keep the base and cover in position with respect to each other. 55 Included within the rim J is a cavity similar to that in the cover, and in this cavity are mounted the various terminals. The cavity is divided up in a manner similar to that of the base by ridges R and Q, which correspond with the 60 ridges R' and Q' of the base B. E E are L-shaped terminals within the cavity, which are adapted to engage beneath the spring-contacts U of the base to secure the base and cover together and complete the circuit, as shown in 65 Fig. 4. T T are the working terminals, to which the leads D D are connected, which leads extend out through a hole H in the top of the cover to form a branch circuit for one or more translating devices. The terminals E E, which 70 are connected with the contacts of the base, are connected by fuses F F with the working terminals T T, screws serving to secure to the respective terminals the clips to which the ends of the fuses are attached, as is the common practice. Hitherto these fuses in wall or 75 ceiling boxes of the type shown herein have been located entirely in a single chamber, so that when they were blown there was a liability to arcing between each terminal E and 80 its corresponding terminal T. This danger is prevented in the following manner: The ridge R divides the chamber between the terminals E and T into two parts, thus separating the terminals; but as provision must be 85 made for the passage of the fuse the ridge is provided with grooves A, in which the fuses are laid. When the cover is mounted upon the base, as shown in Fig. 3, the ridge R' 90 closes up the grooves A in the ridge R, thus forming a very narrow passage for the fuse, inclosed, except as to its ends, and through which passage there is little likelihood of any 95 arc being established. When the cover and base are assembled, not only are the grooves A covered to form the closed passages, but the cavities on the opposite sides of the ridges of both the cover and the base are brought together to form chambers on opposite sides of the adjoining ridges, so that each end portion of the fuses has substantially a separate 100 chamber, the chambers being connected only

by the very small passages for the fuses. Furthermore, the fuse passes through the opening which is formed by the integral portions of the insulating members, which also 5 form the partition itself, and consequently it is not necessary to adapt the main portions of the insulating members for the passage of the fuse. Again, as both the cover and base are formed with depressions, in which are located the ridges which form the partition, each chamber on a side of the partition consists of the corresponding depressions of the cover and base. The operation of replacing a burned fuse is as easy as if there were no 15 inclosed passage for it, as after the cover C is removed a new fuse is simply placed in the groove A in the ridge. Since the terminals T and E are of opposite polarity, the ridges Q of the cover and the ridge Q' of the 20 base when brought together serve to separate these terminals from each other, and thus prevent arcing. Passages P are formed in the cover between the pairs of ridges Q and R, so that the wires D can be led from the terminals T to the depression in the center of the cover and thence out through the 25 hole H.

Having thus described my invention, what I claim as new, and desire to secure by Letters 30 Patent, is—

1. The combination with the members B and C, of the ridges R, R', Q, Q', the terminals T and U and the fuses F, F.

2. The combination with two insulating- 35 disks each formed with a depression and with a ridge in the depression, of means for holding the disks together so that the ridges register to form a partition having an opening, terminals on one disk on opposite sides of its 40 ridge, a fuse connecting said terminals and passing through said opening, and terminals on the other disk which are connected with said terminals when the disks are held together.

45 3. The combination with two insulating-disks each formed with a depression and with a ridge, the ridge on one disk being formed with a groove, means for holding the disks together so that the ridges register to form a partition, terminals on one disk on opposite sides of its ridge; a fuse connecting said terminals and passing through the partition at the groove in said ridge, and terminals on the other disk which are connected with said terminals when the disks are held together.

50 4. The combination with two insulating members which together form a chamber, of two terminals mounted on one of said members, a fuse connecting said terminals, an integral insulating-partition formed by two ridges integral with the two insulating members, which divides said chamber into two parts, the fuse extending through the partition, and means for securing the two insulating members together.

55 5. The combination with two insulating members each formed with a depression, which

together form a chamber, of two terminals mounted on one of said members, a fuse connecting said terminals, a ridge integral with 70 each insulating member, so formed that when the members are brought together to form a chamber, the ridges are located adjacent to each other to form a partition having an opening for the passage of the fuse, said partition 75 dividing the chamber formed by the members into two parts, and terminals on the other disk which are connected with said terminals when the insulating members are held together.

80 6. The combination with two insulating members each formed with a depression which together form a chamber, of two terminals mounted on one of said members, a fuse connecting said terminals, a ridge integral with 85 one of said members and formed with a groove for the reception of the fuse, a ridge integral with the other member, so located that when the members are assembled to form a chamber, the ridges will lie adjacent to form a partition having an opening for the passage of the fuse, said partition dividing the chamber formed by the members into two parts, and terminals on the other disk which are connected with said terminals when the insulating members are held together.

85 7. In a contact device, the combination with an insulating-base and cover adapted to form a chamber, line-terminals in the base, terminals in the cover adapted to engage with those in the base, work-terminals in the cover, fuses connecting the work-terminals with the other terminals of the cover, and an integral insulating-partition through which the fuses pass, which partition is formed by two ridges 100 integral with the base and cover, the chamber being located between the work-terminals and the other terminals of the cover and being divided into two parts by the partition.

105 8. In a contact device, the combination with an insulating-base and cover adapted together to form a chamber, line-terminals in the base, terminals in the cover adapted to engage with those in the base, work-terminals in the cover, fuses connecting the work-terminals with the 110 other terminals in the cover, a ridge integral with the base, and a ridge integral with the cover, so located that when the base and cover are brought together to form a chamber located between the work-terminals and the 115 other terminals of the cover, the ridges form a partition having an opening for the passage of the fuse, said partition dividing the chamber into two portions.

120 9. In a contact device, the combination with an insulating-base and cover adapted to be brought together to form a chamber, of line-terminals on the base, terminals in the cover adapted to engage with those in the base, work-terminals in the cover, fuses connecting the work-terminals with the other terminals in the cover, a ridge integral with the 125 cover and formed with a groove for the reception of the fuse, and a ridge integral with

the base, so located that when the base and cover are brought together to form a chamber located between the work-terminals and the other terminals in the cover, the ridges will 5 form a partition having an opening through which the fuse extends, the chamber being divided into two parts by the partition.

10. In a contact device, the combination with an insulating-base and cover adapted to be brought together to form a chamber, of line-terminals on the base, contact-springs connected therewith, terminals in the cover adapted to engage said contact-springs to connect the cover-terminals with the line-terminals 15 and secure the cover to the base, work-terminals in the cover, fuses connecting the work-terminals with the cover-terminals connected to the spring-contacts, and an integral insulating-partition through which the fuse 20 passes, the chamber formed by the base and cover being divided into two parts by the partition, and said partition being formed by two ridges integral with the base and cover.

11. In a contact device, the combination 25 with an insulating-base and cover, of line-terminals on the base, terminals in the cover adapted to be connected with the line-terminals, work-terminals in the cover, fuses connecting the work-terminals with the other 30 cover-terminals, an integral insulating-par-

tition between each work-terminal and one of the other cover-terminals of opposite polarity, integral insulating - partitions between the terminals which are connected by fuses, openings being formed in the latter partitions 35 for the reception of the fuses, a hole in the top of the cover for the entrance of the branch-circuit wires, and passages from the work-terminals between the partitions to said hole for the reception of said wires.

12. The combination with two insulating members, each formed with corresponding depressions and with corresponding ridges in the depressions, two terminals being mounted on one of the insulating members on opposite sides of the ridge, and a fuse connecting such terminals, whereby when the insulating members are assembled, the terminals will be separated from each other by a partition formed by the ridges, and the portions 45 of the fuse on opposite sides of the partition will lie in chambers formed by the depressions in the insulating members.

In witness whereof I have hereunto set my hand this 28th day of August, 1900.

HOWARD R. SARGENT.
